CONTROL DEVICE FOR LIFTING PINS ON
MOLDING MACHINES

Hans Jakob Rothschild, Schaffhausen, Switzerland, assignor to Georg Fischer Aktiengesellschaft, Schaffhausen, Switzerland

Application February 10, 1949, Serial No. 75,706
In Switzerland December 9, 1948

4 Claims. (Cl. 22—48)

1

The invention relates to a molding machine of the type provided with a vertically displaceable supporting member for the lifting pins, the locking means of which are controlled by a common control valve. In order to prevent the mold from being damaged during the drawing motion it is essential to draw the flask with the mold in perfect alignment with the pattern and without any tilting motion.

In prior art the locking of the lifting pins is effected by hand-operated control means. This causes additional manipulations during the molding cycle. In order to attain the simplification of the operation of molding machines of the above described type the present invention has been developed.

The principal object of the invention is to provide control means for locking the mold lifting pins during the whole mold drawing motion.

Another object of the invention is to provide control means for actuating the vibrator only during the very first beginning of the drawing motion.

The drawings show two embodiments of the invention, the figures representing:

Fig. 1 a cross section through a molding machine with the air control valve for the locking device for the lifting pins,

Fig. 2 a first embodiment of the invention; position of the control valve at the beginning of the mold drawing operation,

Fig. 3 the same embodiment as in Fig. 2; position of the control valve when the mold is drawn,

Fig. 4 the same embodiment as in Fig. 2; position of the control valve when the drawing device is in its lowered position,

Fig. 5 a further embodiment of the invention; position of the control valve at the beginning of the mold drawing operation,

Fig. 6 the same embodiment as in Fig. 5; position of the control valve when the mold is drawn.

Fig. 1 shows the molding machine standard 1 with the laterally rockable head piece 2 and the vertically adjustable press plate 3. The drawing piston 4 is rigidly secured to the machine standard 1. On the drawing piston 4 is vertically slideable the drawing cylinder 5, with which are connected the supporting frame 6, the adjustable members 7 and the lifting pins 8. On the molding machine table 9 rests the molding plate 10 with the pattern 11; the flask 12 with a mold is shown in drawn position.

Supply conduit 14 leads into the pilot valve 16. Conduit 38 is branched-off from the supply conduit 14 and leads into the control valve body 18.

2

Conduit 15 connects the pilot valve 16 with the control valve body 18 and conduit 39 connects the conduit 15 with the upper end of the lifting cylinder 5. The exhaust conduit 17 leads from the pilot valve 16 into the atmosphere.

10 The abutment 18 fixed to the molding machine standard 1 serves as end stop for the stroke length of the drawing cylinder 5 and the arm 20 on top of the drawing cylinder 5 serves for actuating the stem 24 of the control valve 18. Conduit 21 connects the control valve body 18 with the lifting pin locks 13 and the conduit 22 the control valve body 18 with the vibrator 23.

15 Figs. 2, 3 and 4 show the details of a first embodiment of this invention as follows:

20 Slideably mounted in the valve body 18 is the valve stem 24 with the valve piston 36 and the valve cone 37. The screw 25 serves for closing the control valve body 18. The parts 15, 21, 22, 38 and 39 are numbered according to the various conduits as indicated in Fig. 1. The same is the case with the other parts shown in Figs. 2, 3 and 4.

25 Figs. 5 and 6 show the details of a second embodiment of this invention as follows:

20 In a part of the molding machine standard 1 the drawing cylinder 5 slides vertically on top of which is attached the rack 30. Rigidly connected with the machine standard 1 is the control valve body 31 with the valve plug 32 at the one end of which is connected the lever 33 with the weight 34. A part of the hub of the lever 33 is provided with teeth 35 which engage with the teeth of the rack 30. The ports 15, 21, 22, 38 and 39 are numbered to correspond to the conduits as indicated in Fig. 1.

30 The operation of the control valve according to Figs. 1, 2, 3 and 4 is carried into effect as follows:

35 On a molding machine of the type shown in Fig. 1 a mold box or flask 12 has to be drawn or lifted from the pattern 11 on the molding plate 10 by means of the lifting pins 8. At the beginning of the drawing operation the drawing cylinder 5, the supporting frame 6, the adjustable member 7 and the lifting pin locks 13 with the lifting pin 8 rest in their lowermost position. In this position the arm 20 on top of the drawing cylinder 5 stays at the point indicated by interrupted lines in Fig. 1. The condition existing 40 in the control valve body 18 is shown in Fig. 2.

45 The supply conduits 14 and 38 remain under air pressure during the whole molding cycle. Compressed air enters continuously through port 38 of the control valve body 18 and builds up a 50 pressure below valve piston 36 on valve stem 24.

For initiating the drawing operation of the molding machine the lever of the pilot valve 16 is turned into such a position that air from the pilot valve 16 enters into the conduits 15 and 39. As indicated in Fig. 2 the air is entering at 15 and it flows through the valve body 18 to the conduit 21 which leads to the lifting pin locks 13 and to conduit 22 which leads to the vibrator 23. This means that the vibrator 23 begins to work and that the lifting pins 8 are locked by means of the lifting pin locks 13. At the same time air is entering through conduit 39 into the drawing cylinder 5 which commences to ascend together with the parts 6, 7, 8 and 13.

The air pressure in conduit 39 presses the valve piston 36 in upward direction against the arm 20 which ascends and descends together with the drawing cylinder 5. As soon as the ascending movement has been initiated the arm 20 and the valve cone 37 are lifted by the pressure below the valve piston 36 and the valve cone 37 closes the air supply from the conduit 15 to the conduit 22, while the piston 36 closes the air supply from the conduit 15 to the conduit 21. Conduit 22 is now and remains without air pressure; i. e. the vibrator 23 ceases to work. Conduit 21 is now receiving air from the supply conduit 38 and the lifting pins 8 remain locked. This condition corresponds to Fig. 3 and the lifting cylinder 5 proceeds in its ascending motion until it is stopped by the abutment 19. The locking pins and their operation are set forth in greater detail in the description of Figure 3 of Patent No. 2,376,203, belonging to the same assignee.

When the drawing operation is completed the mold 12 may be removed from the still locked lifting pins 8 and now the latter have to be brought back or lowered to their initial position. To effect this descending motion the pilot valve 16 is turned to a position wherein the conduits 15 and 39 are connected with the exhaust conduit 17. The air from the drawing cylinder 5 is exhausted at conduit 17 and the latter, together with the parts 6, 7, 8 and 13 descend into their lowermost position. In this position the arm 20 presses down the valve stem 24 against the action of the air pressure from the conduit 38 below the valve piston 36; the air from the lifting pin locks 13 is exhausted through the conduits 21, 15 and 17.

The operation of the second embodiment of the control valve according to Figs. 1, 5 and 6 is as follows:

The general arrangement and the enumeration of the various conduits remain the same as shown in Fig. 1. In the lowermost position of the drawing cylinder 5, the teeth of the rack 30 are in engagement with the teeth 35 in the hub of the lever 33, which is connected with the valve plug 32. The control valve is in the position shown in Fig. 5.

To initiate the drawing operation of the molding machine the lever of the pilot valve 16 is turned to such a position that air enters from the supply conduit 14 into the conduits 15 and 39. Fig. 5 shows that in the control valve body 31 the air from conduit 15 enters into the conduits 21, leading to the lifting pin locks 13, and conduit 22 leading to the vibrator 23.

At the same time air enters through the conduit 39 into the drawing cylinder 5 and the latter begins to ascend. By means of the rack 30 and the engaging teeth 35 in the hub of the lever 33 the valve plug 32 begins to revolve and closes the air inlet port 15 and the air outlet port 22;

i. e. the vibrator 23 stops working. The valve plug 32 is now in the position shown in Fig. 6 and remains there because of the weight 34 which keeps the valve plug 32 in this position. Conduit 21, which leads to the lifting pin locks 13, now receives air from the conduit 38 which is constantly kept under pressure. The ascending motion keeps out until the drawing cylinder 5 touches the abutment 19.

When the drawing motion is completed the mold 12 is removed from the lifting pins 8 and the descending motion of the drawing cylinder 5, together with the attached parts 6, 7, 8 and 13, may be initiated. To effect this motion the pilot valve 16 is turned to such a position that the conduits 15 and 39 are connected with the exhaust conduit 17. The drawing cylinder 5 begins to descend and when it is nearing its lowermost position the teeth of the rack 30 become engaged with the teeth 35 in the hub of the lever 33. Against the action of the weight 34 the valve plug 32 is now turned to the position indicated in Fig. 5 with the exception that now the conduit 15 is without pressure.

The utilization of a control valve of the above described type offers the advantages that the lifting pins automatically remain locked during the whole drawing operation. This is effected by means of the centrally controlled lifting pin locks. The vibrator 23 remains in operation only during the very first moments of the drawing motion which is sufficient to loosen or free the sand of the mold from the pattern.

I claim:

1. A molding machine, comprising, in combination, a vertically displaceable drawing cylinder, mold-lifting pins, pneumatic locking means connected with said pins for locking the same, means operatively connecting said locking means with said cylinder to move said pins along with said cylinder, a pilot valve, a control valve having a casing and a valve body, supply conduits connecting a compressed air source to said pilot valve and said control valve casing, supply conduits connecting said pilot valve with said drawing cylinder and said control valve casing, whereby said drawing cylinder is actuated by compressed air from the first of said last-mentioned supply conduits, a conduit connecting said control valve casing with said pneumatic locking means, said control valve body being movable in said casing to either of two end positions, said valve body in one of said end positions connecting said pilot valve with said locking means and interrupting this connection and connecting said compressed air source with said locking means, during its movement from said one end position to the other end position, and means carried by said drawing cylinder and engaging said valve body in the lowermost position of said cylinder to maintain the valve body in said one end position while said drawing cylinder is in its lowermost position.

2. A machine in accordance with claim 1, wherein said valve body comprises a valve stem and wherein the last-mentioned means consist of an arm engaging said valve stem in the lowermost position of said drawing cylinder.

3. A machine in accordance with claim 1, wherein said valve body comprises a lever and teeth upon said lever, and wherein the last-mentioned means consist of a rack engaging said teeth in the lowermost position of said drawing cylinder.

4. A molding machine, comprising, in combination, a vertically displaceable drawing cylinder,

mold lifting pins, pneumatic locking means connected with said pins for locking the same, means operatively connecting said locking means with said cylinder to move said pins along with said cylinder, a vibrator, a pilot valve, a control valve having a casing and a valve body; supply conduits connecting a compressed air source to said pilot valve and said control valve casing, supply conduits connecting said pilot valve with said drawing cylinder and said control valve casing, whereby said drawing cylinder is actuated by compressed air from the first of said last-mentioned supply conduits, a conduit connecting said control valve casing with said pneumatic locking means, a conduit connecting said control valve casing with said vibrator, said control valve body being movable in said casing to either of two end positions, said valve body in one of said end positions connecting said pilot valve with said locking means and said vibrator and interrupting these connections during its movement to the

other end position and connecting said compressed air source with said locking means, and means carried by said drawing cylinder and engaging said valve body in the lowermost position of said cylinder to maintain the valve body in said one end position while said drawing cylinder is in its lowermost position.

HANS JAKOB ROTHSCHILD.
